MOVING TARGET APPARATUS

Lucien Jean Théodore Flory, Rocheville, France
Application May 15, 1951, Serial No. 226,358

Claims priority, application France May 22, 1950

5 Claims. (Cl. 273—105.2)

1

The present invention relates generally to movable targets as used in known fashion for the practice of shooting on decoys and adapted to reproduce substantially actual conditions as are encountered during normal shooting when the real bird takes off or flies away.

Devices have already been proposed which reproduce the irregular path followed on the ground by game such as hares, roebucks or like animals, said devices being so constructed as to drive a lure along a predetermined course. In the case of decoy birds, devices have also been proposed which throw into the air a target constituted for example by a clay bird.

The last-named type of device presents a number of disadvantages first because as the target is thrown freely into the air, its path can no longer be altered after it has left the ground so that said path is inevitably rectilinear which seldom corresponds to real conditions encountered in actual shooting and second because the speed of the thrown target has its maximum value at the beginning of its path when it is hurled up and then gradually decreases whereas a living bird rather flies quicker and quicker after having taken flight off the ground.

It is an object of the invention to remedy these disadvantages of the known type of movable targets or decoys and to provide an improved movable target capable of being guided both in elevation and in azimuth during its travel so as to move in a non-rectilinear path.

Another object of the invention is to provide a movable target or decoy for practising shooting on artificial birds the speed of which progressively increases from the moment when this target leaves the ground until the point of its path when the decoy is assumed to have reached its normal flying speed.

A further object of the invention is to provide an improved target or decoy movable both in elevation and in azimuth the travelling speed of which may be altered at will while simulating accelerations of the flight of a living bird.

A still further object of the invention is to provide a movable target device of the aforesaid type comprising means for automatically controlling the motions in elevation and in azimuth of the target or decoy along the desired non-rectilinear path or trajectory, the control means being such that several different trajectories are available for the operator of the device, whereby the hunter cannot know in advance the decoy path or trajectory represented by the target and actual conditions as encountered in real shooting practice are thus more or less reproduced.

2

With these and such other objects as will incidentally appear hereafter, the invention comprises the novel construction and combination of parts that will now be described, with reference to the accompanying diagrammatic drawings exemplifying the same and forming a part of the present disclosure.

In the drawings:

Figure 1 is a perspective view partly in section of the base structure of the target-moving device.

Figure 2 is a perspective view of a power unit which controls the motion of the target or decoy.

Figure 3 is a diagrammatic front representation of the target.

Figure 4 is a front view of a constructional detail of the base structure of the target device.

Figure 5 is an edge view of the device for controlling the motion of the target.

Figures 6 and 7 are detail views in a plane normal to the plane of Fig. 8 showing two companion discs of the controlling device.

Figure 8 is a diagram of the wiring serving the entire target-moving device.

As illustrated by Fig. 1, the target-moving device for practising shooting on decoys comprises according to the invention a pair of hollow posts 1 from the upper ends of which extend guiding cables or rails 2 which are inclined and anchored to the ground at their distal ends by pegs 3. Adequate steadiness of the posts 1 is ensured by means of tensioning cables or guys 4 extending in a direction opposite to that of the guiding cables 2 and anchored to the ground by pegs 5.

Between the guiding cables or rails 2 is interposed a carrier cable 6 arranged transversely thereof and capable of sliding by jockey pulleys 9 attached to its ends on the guiding cables 2 while remaining parallel. Upon the carrier cable

6 is mounted a target 7 which can slide along the cable 6 and to which are secured the ends of a pair of traction-transmitting cables 8. Cables 8 pass through guides or jockey pulleys 9 which serve to move the carrier cable 6 along the guiding cables 2 first upwardly toward the upper ends of the hollow posts 1 and then downwardly to a position adjacent the ground, and back along the ground to a pit 10 in which said cables 8 are wound upon winches 11.

As shown by Fig. 1, the posts 1 are provided adjacent their upper and lower ends with bent portions 12 which form guides facilitating movement of the cables 8 through the posts 1. The target 7 (Fig. 3) which may receive for example a decoy such as a clay bird is slidably fitted upon the carrier cable 6 through the medium of slid-

ing sleeves 13. The cables 8 have one of their ends secured to spaced eyelets 14 provided on the target 7.

Each of the jockey pulleys 9 for the traction-transmitting cables 8 (see Fig. 4) comprises a base plate 15 upon which are journalled three grooved rollers 16 engaging the guiding cable 2, one of these rollers being rendered adjustable by means of a screw-threaded stem 17 and a nut 18 co-operating with a lug 19 on the base plate 15 so as to permit the braking action of the rollers 16 upon the guiding cable 2 to be varied at will. The carrier cable 6 is connected at its ends to each jockey pulley 9 by a spring 20 and the plate 15 carries a curved guide 21 for the engagement of the traction cable 8 which passes through it.

In the pit 10 which is dug in the ground substantially intermediate the anchoring pegs 3 of the guiding cables 2 and between these anchoring pegs, and, the shooting stand, are arranged two power units, each of which (see Fig. 2) comprises a winch 11, an electric motor 22 and a battery 23. Upon the winch 11 is wound, as above stated, the end of the traction cable 3 opposite to its end secured to the target 7. Advantageously, the electric motor 22 is mounted upon a girder frame 24 in which is journalled the winch 11. The driving stress is imparted to the winch 11 from the motor 22 through a sprocket wheel 25 fast upon the shaft of the motor 22 and connected by a sprocket chain 26 to another sprocket wheel 27 fast upon the shaft of the winch. The electric motor 22 has associated therewith an electro-magnetic switch 28 the purpose of which is indicated hereafter.

Each power unit is connected to a common control station arranged on the shooting stand, for example to the rear of the hunter's position. This control station comprises a frame 29 in which is journalled a shaft 30 terminating in a crank 31 and carrying a spirally coiled driving spring 32, one end of which is fastened to the frame 29. A ratchet gear 33 is provided on the shaft 30 and is combined with a lever (not shown) permitting the same to be so tripped as to unwind the spring 32 as indicated hereafter. Upon the shaft 30 is mounted through the medium of a free wheel clutch a sprocket pinion 34 connected by a sprocket chain 35 to a similar pinion 36 fast upon a lay-shaft 37 which carries a further pinion 38 connected in turn by a sprocket chain 39 to a sprocket wheel 40 fast upon a shaft 41 journalled in the frame 29. The shaft 41 has keyed thereto a plurality of collector discs 42, 43 distributed pairwise on two separate parts of the shaft 41 which are interconnected by an insulating coupling 44. The discs 42, 43 are made of conductive metal, and insulating elements are set into their periphery so as to define alternate contacting zones 421 and isolating zones 422 as shown in Figs. 6 and 7.

With the discs 42, 43 co-operate brushes 45, 46 mounted upon an insulating bar 47. These brushes are connected by leads, as hereinafter described, to contacting studs associated with a selecting and distributing cup member 50. The peripheral zones of the two sets of discs 42, 43 are differently distributed upon each disc.

The operation of the control station can be easily understood from the wiring diagram shown in Fig. 8. As illustrated, the positive pole of the battery 23 is connected by a lead 51 to the motor 22 through the switch 28, to which is connected a lead 52 extending from the shaft 41 made of a conductive material. The negative pole of the battery 23 is connected to the motor 22 by a lead 53 and through a lead 54 which is common to

the two power units through a control switch lever 55 which permits the circuit to be selectively open or closed through the selecting cup member 50. The bottom of the cup member 50 is formed with recesses 56 through which project push rods 57 which close or open electric contacts one stud of which is connected by the leads 48 and 49 to the brushes 45, 46. Each contact corresponding to a recess 56 of the cup member 50 is connected to a brush 45 and to a brush 46 co-operating with a pair of discs 43, 42 which are operatively combined and co-operate as stated hereafter.

The operation of the device is as follows:

Assuming the transverse carrier cable 6 to have been brought back to the position of the anchoring pegs 3 of the guiding cables 2 and the traction cables 8 to be unwound to the maximum extent and assuming moreover the target to be on the ground and, to be for example concealed from the hunter who is then on the shooting stand adjacent the control device, the spring 32 is wound up by means of the crank 31 and is held in tightened condition by the ratchet gear 33. A rubber pellet 59 (Fig. 8) is then thrown into the cup member 50 and snaps haphazard into one of the recesses 56 of this cup member while pressing the push rod 57 and therefore closing the corresponding contacts located adjacent said rod. The control circuit is then closed by pressing down the switch lever 55. The latter is adapted to trip the ratchet gear 33 into action while closing the required control circuit. When the lever 55 is closed, the brushes 45, 46 which correspond to that particular recess 56 in which the rubber pellet 59 has snapped are connected through the lead 48, the push rod 57, the cup member 50, the lever 55 and the lead 54 to the negative pole of the battery 23. When the ratchet gear has been tripped, the spring 32 imparts rotation to the shaft 41 and, consequently to the discs 42, 43. When the brushes 45, 46 are on a conductive zone of the periphery of these discs (such as the zones 421 of the discs 42, 43 shown in Figs. 6 and 7) which are associated with the brushes fed from the recess 56 which contains the pellet 59, a dual circuit is completed from the negative pole of the battery and through these discs 42, 43, the shaft 41, the leads 52, the switch 28 and back to the positive pole of the batteries 23. Conversely, these circuits are open whenever an insulating zone of the discs 42, 43 (such as the zone 422 on disc 43 shown in Fig. 7) angularly comes into registration with its brushes 45, 46. When the circuits under consideration are closed, the switches 28 then feed the motors 22 which drive the winches 11 and pull up and wind the traction cables 8.

The conductive zones and the insulating zones are differently distributed for each disc of a pair of companion discs 42, 43 such as the disc shown in Figs. 6 and 7, i.e. co-operating with the brushes 45, 46 connected to one and the same push rod 57. However, the distribution of said zones is preferably such that at least one motor feeding circuit is always completed during a rotational cycle of the discs 42, 43. When only one circuit is completed, one winch 11 is revolved by the corresponding motor 22 so that the target 7 is pulled by one cable 8 and is shifted along the carrier cable 6 toward the one or the other of the jockey pulleys 9, the carrier cable 6 being slowly drawn toward the upper ends of the posts 1 owing to the reduction of the total length of unwound traction cable 8 assuming both cables 8 to be jointly considered. Conversely, when both feeding cir-

cuits of the motor 22 are closed, the winding of the two cables 3 shifts the target 7 substantially parallel to the guiding cables 2. Taking into account the acceleration of the speed of rotation of the motors 22 when they begin to rotate, it will be understood that the target 7 performs a path along an irregular line while undergoing progressive accelerations which correspond to the flying conditions of a living bird.

It will be easily understood that the distribution of the conductive zones and insulating zones on the discs 42, 43 varies for each pair of discs and that in each case a different path or trajectory is thus imparted to the target 7, said path being determined haphazard among a range of possibilities depending upon the recess 56 into which the rubber pellet 59 has snapped so that the hunter can never foretell the trajectory of the flying target or decoy and thus experiences circumstances more or less similar to those of actual shooting on living birds.

Minor constructional details may be varied without departing from the scope of the subjoined claims.

What is claimed is:

1. A target practice device reproducing the take off and the flight of a living bird, comprising a pair of spaced posts, two inclined parallel guiding cables taut between the top of said posts and the ground, a pair of jockey pulleys slidably mounted on said cables, a transverse carrier cable connected at each end to said jockey pulleys, a target slidably mounted on said transverse carrier cable, a pair of traction transmitting cables, winding means for each traction transmitting cable, power means combined with each winding means, each traction-transmitting cable being secured at one end to said target and being guided to the top of said posts and wound at the other end on said winding means, and means for selectively controlling said power means so as separately to control said winding means and to drive said target along a sinuous path according to the differential action resulting from the operation of said winding means, the hunter standing at such a position that the target flies away from him as said power means are operated.

2. A target practice device comprising a pair of spaced posts, two inclined parallel guiding cables taut between the top of said posts and the ground, a pair of jockey pulleys slidably mounted on said cables, a transverse carrier cable connected at each end to said jockey pulleys, a target slidably mounted on said transverse carrier cable, a pair of traction-transmitting cables, a pit, a pair of winches mounted in said pit, a pair of electric motors for operating said winches, each traction-transmitting cable being secured at one end to said target, being guided along said carrier and guiding cables to the top of said posts and being wound at the other end on one of said winches, a source of electric energy for supplying current to said motors, switching means inserted between said source and said motors, and control means for operating said switching means so as separately to control the operation of said electric motors and winches associated therewith and to drive said target along a sinuous path according to the differential action resulting from said con-

trol, the hunter standing at such a position that the target flies away from him as said motors are operated.

3. A target practice device comprising a pair of spaced posts, two inclined parallel guiding cables taut between the top of said posts and the ground, a pair of jockey pulleys slidably mounted on said cables, a transverse carrier cable connected at each end to said jockey pulley, a target slidably mounted on said transverse carrier cable, a pair of traction-transmitting cables, a pit, a pair of winches mounted in said pit, a pair of electric motors for operating said winches, each traction-transmitting cable being secured at one end to said target, being guided along said carrier and guiding cables to the top of said posts and being wound at the other end on one of said winches, a source of electric energy for supplying current to said motors, a pair of switches interposed between said source and said motors, a shaft made up of two parts angularly rigid with each other, an insulating element interposed between said parts, pairs of collector discs keyed on said parts of the shaft, conducting and insulating zones provided at the periphery of said collector discs, brushes pressed against said peripheral zones of the discs, a selector device, and conductors leading from said source of electric energy to said switches through said selector device and said collector discs of each pair to form control circuits, a switch and a collector disc of each pair being series connected in each circuit, and the circuits including the two discs of a pair being connected in parallel, so that the target is driven along a sinuous path which is defined by the combination of the peripheral zones of each disc of a pair.

4. A target practice device according to claim 3, wherein the selector device comprises a cup member, recesses provided in the bottom of said cup member, push rods projecting within said recesses, and carrying a contact member at their lower end, pairs of contacts arranged in front of said contact members of the push rods, each contact of a pair being connected to a brush pressed against a collector disc of a pair, so that both discs of a pair are electrically operative when a push rod is depressed, and a ball removably located in said cup member for nesting itself into one of said recesses for depressing a push-rod and closing two control circuits including both discs of a pair so as separately to switch in each electric motor.

5. A target device according to claim 4, wherein the peripheral conducting and insulating zones are differently distributed from one disc to the other disc of the same pair and also from one pair of discs to the other pair.

LUCIEN JEAN THÉODORE FLORY.
